UNITED STATES PATENT OFFICE.

CHARLES P. SWICK, OF WATERBURY, AND FRANK O. KRANTZ, OF OAKVILLE, CONNECTICUT, ASSIGNORS TO AMERICAN RING COMPANY, OF WATERBURY, CONNECTICUT, A CORPORATION OF CONNECTICUT.

METHOD OF MAKING KNOBS.

1,407,960.

Specification of Letters Patent. Patented Feb. 28, 1922.

Application filed June 16, 1920. Serial No. 389,358.

To all whom it may concern:

Be it known that we, CHARLES P. SWICK and FRANK O. KRANTZ, citizens of the United States, residing, respectively, at 5 Waterbury, in the county of New Haven and State of Connecticut, and at Oakville, in said county and State, have invented a certain new and useful Method of Making Knobs, of which the following is a specification, reference being had therein to the accompanying drawings.

Our invention relates to a new and improved method of making knobs or the like, referring more particularly to the type of 15 metal knobs that are designed to be held against rotation in their operative position.

It is the object of this invention, among other things, to produce by our method a 20 knob of this character that will have integral projections upon the contact face thereof produced by means that insures one or more projections of any desired shape that may or may not be uniform in shape, and each having a solid base integral with the 25 knob itself.

To these and other ends, our invention consists in the method of making knobs substantially as hereinafter described and more particularly pointed out in the claims.

30 Referring to the drawings in which like numerals of reference designate like parts in the several figures:

Figure 1 is an elevation of a partially 35 formed knob and still attached to the bar out of which it is constructed; and illustrating one of the steps of our method;

Figure 2 is an end view thereof;

Figure 3 is a fragmentary end view of one 40 form of tool for operating upon the contact face of the knob;

Figure 4 is a fragmentary view of the completed knob, and a sectional view of a pair of dies, for holding the knob during one of the operations of our process;

45 Figure 5 is a fragmentary view of the lower end of one form of tool for producing projections upon the knob;

Figure 6 is a view of the contact face of the completed knob; and

50 Figure 7 is a modified form of tool.

The type of knob such as is shown in the drawing and described herein to illustrate our invention is such as is generally used for

furniture as a draw pull or the like, although, of course, it is not limited thereto. 55 What has been heretofore impossible to provide with a solid turned knob is means upon the contact face thereof to prevent its rotation, without attaching auxiliary parts thereto, or so forming projecting parts 60 thereon that they have no solid base.

Our invention is largely designed to produce a solid turned knob with projections or prongs thereon integral therewith, these being uniform in shape and size or not as desired, and each having a solid base and tapered so as to more readily facilitate the entrance thereof into the surface with which the knob is connected.

Knobs of this type are usually formed 70 from a bar 10 of metal by turning a portion thereof into the desired shape. A knob so turned but not severed from the bar is shown in Figure 1 and designated by the numerals 11. Of course the illustration discloses only 75 one of the many shapes in which these knobs can be turned. The contact face 12 of the knob is provided with a projecting ring 13 which is tapered on both sides to its outer edge 14 and the knob base upon each side of 80 the ring 13 is provided with recesses 15 and 16 which are below the contact face 12. A central recess 17 is also provided in the base to guide the drill for the opening 18 therein which is subsequently threaded as shown in 85 Figure 4.

One form of tool by which the base of the knob can be formed substantially as above described is shown in Figure 3 and designated by the numeral 19 the diameter of 90 which may be varied as desired. After the knob 11 has been formed and severed from the bar it is held between a pair of dies 20 and 21 with the ring 13 projecting beyond the face thereof. A tool 22 having a plurality of recesses 23 therein corresponding in shape with the finished projections or prongs 24 and substantially in cross-section the same size and shape as the cross-section of the ring 13 is now brought up against the 95 knob and such portions of the ring 13 as lie between the recess 23 in the tool 22 are compressed or flattened out. The remaining portions of said ring form the projections or prongs 24 which as shown are of substantially uniform size and shape, have a solid 100 105

base and are pointed toward the top. By varying the shape of the sides of the ring 13, or the recesses 23 in the tool 22, or both, the shape of the prongs can also be changed 5 from those herein shown. Eight projections or prongs 24 are shown in the drawings, but it is obvious that a quarter or less number can be formed equally as well.

- The face of the tool 22, may, if desired, 10 be provided with a ring 25, having the recesses 23 therein, the diameter thereof being such as to permit its entering the recesses 15 and 16 without any portion of the total engaging the contact face 12.
- 15 If the metal in the ring 13 has a tendency to flow outwardly by the action of the tool 22 thereon the recesses 15 and 16 accommodate this movement so that upon completion of the knob the contact surface 12 is straight 20 and all displaced metal is below the face thereof.

While we have shown in the drawings a knob cut from a solid bar, our method is equally applicable to a cast knob, a ring 13 25 being turned or trued up upon the contact face thereof.

Minor changes and alterations may be made within our invention aside from those herein suggested and we would therefore 30 have it understood that we do not limit ourselves to the exact construction herein shown and described, but claim all that falls fairly within the spirit and scope of our invention.

What we claim is our invention, and desire to secure by Letters Patent, is:

1. A method of making knobs or the like, which consists in forming a projection upon the contact face thereof, and then compressing a portion of said projection, the non-compressed portion thereof forming one or more prongs.

2. A method of making knobs or the like, which consists in forming a projection upon the contact face thereof, then compressing a portion of said projections, and shaping the remaining portion to form one or more prongs.

3. A method of making knobs or the like, which consists in forming a projection upon the contact face thereof, one or more sides of which form faces of the prong or prongs hereinafter mentioned, and then compressing a portion of said projection, the non-compressed portion thereof forming one or more 55 prongs.

4. A method of making knobs or the like, which consists in forming a projection upon the contact face thereof, two sides of which form two faces of the prong or prongs hereinafter mentioned, and then compressing a portion of said projection, the non-compressed portion forming one or more prongs, two faces of which are formed during said compression action.

5. A method of making knobs or the like, which consists in forming a projecting ring upon the contact face thereof and then compressing a portion of said ring, the non-compressed portion thereof forming one or more prongs.

6. A method of making knobs or the like, which consists in forming a projecting ring upon the contact face thereof and then compressing a portion of said ring, the non-compressed portion thereof forming one or more 75 prongs, equally distant from the center of said knob upon said contact face.

7. A method of making knobs or the like, which consists in forming a projecting ring upon the contact face with flaring sides 80 which terminate and join at a point upon the outer edge of said ring, and then compressing a portion of said ring; the non-compressed portion forming one or more prongs.

8. A method of making knobs or the like, which consists in forming a projecting ring upon the contact face thereof with sides which taper toward each other away from the said contact face, then compressing a portion of said ring, the non-compressed portion forming one or more prongs; two sides thereof being formed from the sides of said ring and the others being formed so as to taper outwardly during the compression of said ring.

9. A method of making knobs or the like, which consists in forming a projecting ring upon the contact face thereof and then compressing a portion of said ring, the non-compressed portion forming one or more prongs, which are pointed at their outer ends, a portion of the tapered sides being originally the sides of said ring and the other sides being formed during the compression thereof.

In testimony whereof we have hereunto affixed our signatures.

CHARLES P. SWICK.
FRANK O. KRANTZ.
